DESIGN FOR A SPOON OR SIMILAR ARTICLE

John Vassos, New Canaan, Conn., assignor to
R. Wallace & Sons Manufacturing Company,
Wallingford, Conn., a corporation

Application September 8, 1934, Serial No. 53,233

Term of patent 14 years

To all whom it may concern:

Be it known that I, John Vassos, a citizen of the United States, residing at New Canaan, in the county of Fairfield and State of Connecticut, have invented a new, original, and ornamental Design for a Spoon or Similar Article, of which the following is a specification, reference being had to the accompanying drawing, forming part thereof.

Fig. 1 is a face view of a spoon or similar article;
Fig. 2 is a back view of the same; and
Fig. 3 is a sectional view on the line 3—3 of Fig. 1 on an enlarged scale.

I claim:

The ornamental design for a spoon or similar article as shown.

JOHN VASSOS.
